CLAIM

The ornamental design for a gift bag, as shown and described.

DESCRIPTION

FIG. 1 is an end view illustrating ornamental features of the gift bag;

FIG. 2 is side view thereof; and,

FIG. 3 is a top view thereof.

The lines indicating shading in FIGS. 1-3 are for illustrative purposes only and form no part of the claimed design. Additionally, the gift bag handle and interior are shown in broken lines for illustrative purposes only and forms no part of the claimed design.

1 Claim, 3 Drawing Sheets

FIG. 3
